WINDING MECHANISM

Edwin J. McIlvried, Akron, and Norman H. Nye,
 Cuyahoga Falls, Ohio, assignors to The Vaughn
 Machinery Company, Cuyahoga Falls, Ohio, a
 corporation of Ohio

Application January 15, 1936, Serial No. 59,252

16 Claims. (Cl. 242—25)

This invention relates to winding apparatus, and more particularly, to improved apparatus of this kind adapted for use in winding various kinds of material and especially suitable for relative high speed winding of comparatively delicate strand material, such as fine wire.

The principal object of the present invention is to provide improved winding apparatus having means for automatically controlling one or more winding functions in response to changes in the depth of the material on the spool.

Another object of the invention is to provide improved winding apparatus having a spool adapted to be driven at different speeds, and means for automatically controlling the speed of the spool to compensate for changes in the effective diameter of the spool comprising a member in cooperating relation to the spool and adapted to be moved substantially proportionately with changes in the depth of material thereon.

Still another object of the invention is to provide novel control means for strand winding apparatus comprising a member in cooperating relation to the spool and adapted to be moved in response to variations in the depth of material on the spool but which member is prevented from contact with the material by an intervening medium.

A further object of the invention is to provide a novel control for winding apparatus comprising a member adapted to be moved in response to changes in the depth of material on the spool and which member has a discharge opening presented to the material and is prevented from contact with the material by fluid discharged thereagainst through said opening.

Yet another object of the invention is to provide improved winding apparatus having an oscillating guide for directing the material to different portions of the spool, and wherein the travel of such guide is automatically varied by means operated in response to changes in the depth of material on the spool.

Other objects and advantages of the invention will be apparent from the following description when taken in conjunction with the accompanying sheet of drawings, wherein

Fig. 1 is an elevational view, with parts in section, showing a winding mechanism embodying our invention; and

Fig. 2 is a sectional view thereof taken as indicated by line 2—2 of Fig. 1.

Although our invention, when suitably embodied in winding machines, may be adapted to the winding of various kinds of material, it is es-

pecially applicable to high speed winding of comparatively delicate strand material, such as fine wire. In the accompanying drawing, to which more detailed reference will now be made, we have shown winding apparatus embodying our invention and which is particularly suited to winding service of the character last mentioned. It will be understood, however, that the illustration of this particular machine is by way of example and that the invention is not necessarily limited to this machine nor to the winding of any particular strand material.

The machine illustrated in this instance is provided with a suitable frame 10, which may be a cast metal frame of hollow construction to enclose and protect various parts of the mechanism. A rotatable arbor 11 suitably mounted on the frame is adapted to receive a spool 12 upon which the wire, or other strand material, 13 is to be wound. The arbor may be suitably connected with a drive shaft 14 which extends into the chamber of the frame 10 and is supported on the frame by suitable bearings 15 provided thereon.

The spool 12 may be driven at different speeds by power transmitted thereto through an adjustable transmission device 16. The transmission device illustrated in this instance is of the friction type and comprises a friction disk 17 and a roller 18 which is drivingly connected to the shaft 14 and engaged by the face of the friction disk. It will be understood, of course, that any other well known form of adjustable transmission may be used in place of the friction device just described. The disk 17 may be driven from any suitable source of power, such as from a motor or line shaft, with which the pulley 20 may be connected as by means of a belt.

The disk 17 is connected with the pulley 20 by means of a shaft 21 which, in this instance, is a flexible shaft having a pair of universal joints 22 and 23 therein. The outer end of the shaft may be mounted in a stationary bearing, such as the bearing 24 provided on the frame 10, but the inner end of the shaft is shiftable laterally for the purpose of shifting the disk 17 so that different portions thereof may be brought into driving engagement with the roller 18 to vary the transmission adjustment or ratio.

To provide for such shifting of the disk 17, we mount the inner end of the shaft 21 in a shiftable bearing 26 which is carried on one arm of a pivoted control member preferably in the form of the lever 27. The pivot for the lever 27 may be a stud 28 which is mounted in a part of the frame 10. The lever 27 is, preferably, slidably as well as

pivotedly mounted on the pin 28 and a compression spring 29 may be disposed between the lever and the frame to normally urge the lever in a direction to press the disk 17 against the roller 18. 5 Shifting movement of the disk sufficient for different transmission ratios is permitted by providing the shaft 21 with a spline connection 30 adjacent one of the universal joints.

As indicated above, one of the important features of our invention is the provision of means for automatically controlling the speed of the spool 12 to compensate for changes in the effective diameter of the spool which results from the building up of the material thereon. For the accomplishment of this function we provide a movable member, preferably in the form of a hollow swinging arm 32, which is adapted to be moved in response to changes in the depth of the material on the spool and which has operative connection with the variable speed transmission 16. The hollow arm 32 may be pivotally mounted adjacent the spool 12 by being provided with a shaft extension 33 which is rockably mounted in and extends through a suitable bearing 34. The outer free end of the arm 32 is disposed in co-operating relation to the spool 12 and may be of nozzle-like form and provided with a discharge opening 35 which is presented to the material on the spool.

30 For operatively connecting the extension shaft 33 of the arm 32 with the shiftable lever 27, we provide a stop or ratchet 37 which is pinned upon or otherwise connected to the shaft and which has an angularly disposed step-like series of teeth 38 or shoulders 38 adapted to be engaged by a pawl-like arm or extension 39 provided on the lever 27. A tension spring 40, suitably arranged to act on the lever 27, normally holds the pawl 39 in engagement with some one of the teeth of the series 40 38, and the particular tooth with which the pawl engages at a given instant determines the position of the disk 17 with respect to the roller 18.

From the arrangement just described it will be seen that swinging movement of the hollow arm 32 outwardly relative to the spool 12 will cause swinging movement of the ratchet 37 in a direction which may be conveniently referred to as into the plane of the paper upon which this drawing is made, and such movement of the ratchet allows the pawl 39 to successively engage the individual teeth of the series 38. As the pawl 39 moves from one tooth to the next of this series the inner end of the shaft 21 is moved to the left, as seen in Fig. 2, and the point of contact of the roller 18 with the disk 17 approaches correspondingly closer to the axis of rotation of the disk with the result that the speed of rotation of the spool 12 will be correspondingly reduced.

If the arm 32 were allowed to contact directly with the material on the spool, more or less damage would result to the material, and to avoid this we provide for an intervening medium between the arm and the material. This intervening medium may conveniently be a fluid, preferably air, which is discharged through the nozzle opening 35 at the free end of the arm and against the material on the spool. Air for this purpose may be obtained from any suitable source, and may be supplied to the arm 32 through a pipe 40 and the hollow gland 41 into which a portion of the arm 32 may extend. The air is supplied to the arm 32 at such pressure that it will be discharged against the material of the spool at a substantially constant velocity so that the free end of the arm will be in cooperating relation to

the surface of the material on the spool but maintained just out of contact therewith.

As another feature of our invention we have provided novel means for controlling an oscillating guide which directs the material to different portions of the spool. This control makes possible the use of a winding spool having oppositely tapered end flanges, as shown in Fig. 2. Before proceeding with the description of this improved guide control, we wish to point out that certain important advantages make it desirable to use a winding spool having such oppositely tapered end flanges, but that a satisfactory guide or laying device has not been available heretofore which would permit the use of a spool of this form. In passing, it might be mentioned that one advantage in using a winding spool having tapered end flanges is that it eliminates the tendency for strands of relatively fine wire to become gripped or fouled adjacent the flanges of straight-flanged spools, which tendency is well understood by those skilled in this art.

The strand guiding mechanism with which our novel control may be used, may comprise a reciprocable bar 45 having a pair of guide fingers 46 between which the strand 13 extends. The bar 45 may be supported and guided in a suitable bearing 47 so as to have reciprocating movement substantially parallel with the axis of spool rotation. The bar 45 may be normally urged in one direction, for example inwardly of the frame 10, by means of a compression spring 48 disposed between the bearing 47 and a shoulder 49 provided on the bar. Movement of the bar 45 in the opposite direction may be caused by a fulcrumed lever 50 having one end thereof in engagement with the inner end of the bar 45 and the other end thereof engaged by one end of a reciprocable bar or plunger 52. The plunger 52 may have at its opposite end a roller 53 which engages a driving cam 54. The cam 54 may be driven by any suitable means which rotates the cam shaft 55 and, when so driven, causes reciprocation of the bar 52. Such reciprocation of this bar causes rocking of the lever 50 which, in turn, causes reciprocation of the bar 45 and the desired oscillating travel of the guide fingers 46.

To automatically vary the travel of the fingers 46, so that the strand will be properly wound on the tapered end flanges as well as the cylindrical barrel part of the spool, we provide means for varying the effective lever arm of the rocking lever 50. This means may comprise a shiftable support 56 for the fulcrum 57 upon which the lever 50 is mounted. The support 56 may be in the form of a block which is slidable in ways provided by the spaced guide members 58 and 59.

To render this variable-travel guide device responsive to movement of the control member 32, we provide the pivoted lever 27 with an additional arm 60 which may be operatively connected with the shiftable block 56, as by means of a gear sector 61 on the arm and meshing with a rack 62 on the block.

From the arrangement just described it will be seen that as material builds up or grows on the spool and the arm 32 is moved outwardly relative to the spool axis, the ratchet 37 will be swung in the direction mentioned above, to permit the lever 27 to be swung in a counter-clockwise direction on its pivot by means of the tension spring 40. This movement of the lever 27 shifts the block 56 downwardly, as seen in Fig. 2, and thus increases the effective lever arm length of the lever 50 acting on the bar 45 and thereby

causes an increase in the length of travel of the guide fingers 46, such that the strand 13 is properly wound against the tapered flanges of the spool.

5 From the foregoing description and the accompanying drawing it will now be readily understood that we have provided improved winding mechanism wherein the speed of the spool is automatically changed to compensate for variations occurring in the effective diameter of the 10 spool as the result of the material building up thereon, and that such automatic changes in the spool speed are produced by means which comprises a member in cooperating relation to the spool and adapted to be moved in response to 15 changes in the depth of material thereon.

It will be understood furthermore that the 20 movable control member which cooperates with the spool is prevented from direct contact with the material by an intervening medium, and that the presence of such intervening medium may be obtained by providing the member with an opening which is presented to the material on the spool and through which fluid is discharged 25 against the material.

It will also be readily understood from the foregoing description and the drawing that we have provided novel means for automatically varying the travel of an oscillating guide whereby the 30 strand will be properly directed to different portions of the spool, and the use of which novel mechanism permits the strand to be efficiently wound on spools having tapered end flanges. It will be understood, further, that this automatic control for the strand guide involves the 35 use of the above mentioned movable control member which is disposed in cooperating relation to the spool adapted to be moved in response to changes in the depth of material wound thereon.

40 Throughout the claims and specification we have referred to the part upon which the strand is wound as being a "spool" and, in this connection, we wish it to be understood that by the word "spool" we intend to include any member 45 or device of suitable nature and upon which the strand may be wound.

While we have illustrated and described our improved winding apparatus in a somewhat detailed manner, it will be understood, of course, that the invention is not to be regarded as limited to any particular winding apparatus nor to the winding of any particular strand material, but that the invention includes all modifications and changes which do not constitute a departure from the spirit of the invention and the scope of the 55 appended claims.

Having thus described our invention, we claim:

1. In apparatus of the character described the 60 combination of a rotatable spool adapted to be driven at variable speed, and a control therefor comprising a member adapted to be moved substantially proportionately to variation in the depth of material on the spool, said member being provided with means for discharging fluid against the material to prevent contact of the member therewith.

2. In combination, a rotatable spool adapted to 70 have material wound thereon, a member in cooperating relation to said material and adapted to be actuated upon change in the depth of material on the spool, means controlled by said member for correspondingly varying the speed of rotation of the spool, and means maintaining fluid 75 between said member and the material on the

spool for preventing contact of the member with the material.

3. In combination, a rotatable spool adapted to have material wound thereon, a member in co-operating relation to said material and adapted to be actuated upon change in the depth of material on the spool, means controlled by said member for correspondingly varying the speed of rotation of the spool, said member being hollow and having an opening presented to the material, and means for causing fluid to be discharged through 10 said opening and against the material.

4. In winding apparatus the combination of a 15 rotatable spool upon which material is adapted to be wound, means for driving the spool including a transmission having adjustment for different spool speeds, a movable member in cooperating relation to the spool and having operative connection with said transmission for effecting adjustment thereof, said member being hollow and 20 having an opening presented to the material on the spool, and means for causing fluid to be discharged through said opening and against said material.

5. In winding apparatus the combination of a 25 rotatable spool upon which material is adapted to be wound, means for driving the spool including a transmission having adjustment for different spool speeds, a movable nozzle having operative connection with said transmission for 30 effecting adjustment thereof and also having a discharge opening presented to the material on the spool, and means for causing a substantially constant flow of fluid through the nozzle opening and against the material.

35 6. In winding apparatus the combination of a rotatable spool upon which material is adapted to be wound, means for driving the spool including a transmission having a step-by-step adjustment for different spool speeds, a hollow arm 40 mounted to swing relative to the spool and having an opening presented to the material on the spool, means for causing a flow of fluid through said arm and against the material, and means whereby movement of said arm causes actuation 45 of the step-by-step adjustment.

7. In winding apparatus the combination of a 50 rotatable spool upon which material is adapted to be wound, an oscillating device for guiding the material to different portions of the spool, and means for automatically varying the travel of the guiding device in response to change in the depth of material on the spool, said means including a shiftable member provided with means 55 for discharging fluid against the wound material to prevent contact of the shiftable member therewith.

8. In winding apparatus the combination of a 60 rotatable spool having tapered flanges, an oscillating device for guiding the material being wound to different portions of the spool, and means operable to increase the length of travel of the guiding device in response to an increase in the depth of material on the spool, said means including a shiftable member provided with means 65 for discharging fluid against the wound material to prevent contact of the shiftable member therewith.

9. In winding apparatus the combination of a 70 rotatable spool upon which material is adapted to be wound, an oscillating device for guiding the material to different portions of the spool, means for varying the travel of the guiding device comprising a member in cooperating relation to the spool and movable substantially proportionately 75

- with changes in the depth of material on the spool, and means for supplying a fluid medium to prevent contact of said member with the material.
10. In winding apparatus the combination of a rotatable spool upon which material is adapted to be wound, an oscillating device for guiding the material to different portions of the spool, and means for varying the travel of the guiding device comprising a member in cooperating relation to the spool and movable substantially proportionately with changes in the depth of material on the spool, said member having an opening presented to the material and being held out of contact therewith by fluid discharged through said opening against the material.
11. In winding apparatus the combination of a spool adapted to be rotated at different speeds, an oscillating device for guiding material to different portions of the spool, means responsive to changes in the depth of material on the spool for automatically varying the spool speed and the travel of the guiding device, and means for supplying fluid medium to prevent contact of said responsive means with the material.
12. In winding apparatus the combination of a rotatable spool, a transmission device for varying the spool speed, a reciprocable guide for directing the material to different portions of the spool, a lever actuating said guide, a shiftable fulcrum for said lever, a member in cooperating relation to said spool and adapted to be moved outwardly therefrom as the material builds up on the spool, a ratchet having connection with said member and provided with a series of teeth, and another member having operative connection with said transmission device and with said shiftable fulcrum and also having a pawl engaging said ratchet.
13. In winding apparatus the combination of a rotatable spool, a variable transmission for driving the spool at different speeds, a control member having operative connection with the transmission for adjusting the same, spring means tending to shift said control member in a direction to reduce the spool speed, a movable stop normally preventing shifting of said control member by the spring, and means operable in response to the growth of material on the spool for moving said stop.
14. In winding apparatus the combination of a rotatable spool, a variable transmission for driving the spool at different speeds, a variable-travel guide device for guiding the material to different portions of the spool, a control member having operative connection with the transmission for varying the spool speed and with the guide device for varying the travel thereof, spring means tending to shift said control member in a direction to reduce the spool speed and to increase the length of travel of the guide device, a movable stop normally preventing shifting of the control member by the spring, and means operable in response to growth of material on the spool for moving said stop.
15. In winding apparatus the combination of a rotatable spool, a variable transmission for driving the spool at different speeds, a control member having operative connection with the transmission for adjusting the same, spring means tending to shift said control member in a direction to reduce the spool speed, a movable stop normally preventing shifting of said control member by the spring, an arm operable in response to the growth of material on the spool for moving said stop, and means for supplying fluid medium to prevent contact of the arm with the material.
16. In winding apparatus the combination of a rotatable spool, a variable transmission for driving the spool at different speeds, a variable-travel guide device for guiding the material to different portions of the spool, a control member having operative connection with the transmission for varying the spool speed and with the guide device for varying the travel thereof, spring means tending to shift said control member in a direction to reduce the spool speed and to increase the length of travel of the guide device, a movable stop normally preventing shifting of the control member by the spring, an arm operable in response to the growth of material on the spool for moving said stop, and means for supplying fluid medium to prevent contact of the arm with the material.
